UNITED STATES PATENT OFFICE.

EDWARD M. HARRIS, OF RIVERSIDE, NEW JERSEY.

COMBINATION CONTAINER.

Application filed January 6, 1926. Serial No. 79,658.

This invention relates to screw cap containers, and more particularly to a combination container and cutting blade or knife which is exteriorly hinged to the bottom or 5 closed metal cap portion of a tubular container, and adapted to be folded therein when not in use. The principal object of the invention is to provide a container which is commonly used for vending a flexible 10 commodity, such as sheet rubber patching material, with a foldable cutter or knife, which is hinged exteriorly of the bottom end and adapted for cutting portions of said material, and using the container as a gripping member.

Another object of the invention is to provide a container as specified, which has an elongated slot in its bottom end for normally receiving a blade which is hinged exteriorly of and at one end of the slot, and adjacent the perimeter of the flanged bottom member for limiting the opening movement of the blade.

A further object of the invention is to provide a combination container with a hinged cutting blade which is adapted to be normally positioned inwardly of the container by means of a slot in the bottom end thereof, and said cutting blade provided with an 10 offset ear for limiting the inward or closing movement of the blade, and a protruding indentation at the side of the blade, midway between the offset ear and the cutting edge for retaining the said blade in its closed 15 normal position.

Other objects of the invention will appear in the following detail description, and in the accompanying drawing wherein:

Figure 1—is a view in elevation of the 20 container with the cutting blade in open position.

Figure 2—is a longitudinal section through the container with the cutting blade shown 25 closed in full lines and extended in dotted line.

Figure 3—is a plan view of the bottom end of the container showing the blade hinged thereto.

Referring more particularly to the drawing, the combination container and cutting member therefor comprises a tubular container 10 having a metal screw cap 11 at its top end 12 thereof, and a bottom metal cap 13 which is fixedly secured to the bottom end of the tubular portion 14 of the con-

tainer 10. The bottom metal cap 13 which is provided in my invention, comprises a flanged metal cap which is provided centrally with an elongated slot 15 which extends across the bottom 16 of the cap 13, 60 and each end of said slot extends adjacent to the flanged rim 17 of the bottom cap 13.

Pivots attached to and outwardly of the bottom 16 of the cap 13, at one end of the slot 15, is a hinged pin 18 adapted for 65 hingedly receiving thereon, a hinge barrel 19 formed on one end of the cutting blade 20 and said blade positioned on said pin on the longitudinal center line of the slot 15, and adapted to be normally positioned in 70 said slot and extending inwardly of the bottom 16 when not in use. Its inward or closing movement is limited by a laterally extending offset ear 21 which is formed on the upper edge of the blade 20, for engagement 75 on the bottom surface 16 adjacent one edge of the slot 15. The cutting blade 20 is further provided intermediate the offset ear 21 and the cutting edge 22 of the blade 20, with an indentation 23 which protrudes from one 80 side of the blade 20 for engagement against one edge of the slot 15 when the blade is being placed in its normally closed position, and said indentation adapted to extend inwardly of the slot 15 for frictional engagement 85 on the inner surface of the bottom 16 immediately adjacent one edge of said slot for retaining said cutting blade in its normally closed position. Similarly, when the cutting blade 20 is withdrawn from the slot 90 15, and in an upwardly and rearwardly extended position, the top edge of the blade 20 will engage and bear against the flange 95 rim 17 of the cap 13, when in use for cutting purposes.

From the foregoing description, it will be readily apparent that when it becomes necessary to cut a portion of any flexible material from the entire piece contained in the described container, it is only necessary 100 to remove the material from the container and withdraw the blade out of the bottom of said container and cut the desired material, using the tubular container as a gripping member, in a manner similar to the 105 handle on a knife.

It is, of course, to be understood, that the invention may be constructed in various other manners, and the parts associated in different relations, and therefore, I do not 110

desire to be limited in any manner, except as set forth in the claims hereunto appended.

What I claim is:

- 5 1. In combination with an annularly flanged bottom closure disc for a cylindrical container including a removable screw cap therefor, of an elongated rectangular slot in said closure disc, a cutting blade having a
- 10 hinged blade formed on one end thereof at right angles thereto hingedly connected to the underside of said bottom closure disc adjacent one end of said slot and centrally therewith, said blade adapted for folding
- 15 placement in said slot, the annular flange on said closure disc formed to extend outwardly at right angles to said bottom closure disc and adapted for limiting the opening movement of said cutting blade, and laterally
- 20 projecting means formed on one side of said cutting blade for retaining said blade in said slot in a normally folded position.

- 25 2. In combination with the bottom end of a tubular container, an elongated rectangular slot in said bottom member, a cutting blade hingedly connected to the underside

of said bottom end, adjacent one end of said slot centrally therewith, said cutting blade adapted for foldable placement in said slot, means for retaining said cutting blade in 30 said slot, a laterally extending ear formed on said cutting blade, for limiting the closing movement of said blade, and an annular flange on said bottom end for limiting the 35 opening movement of said blade.

3. In combination with the flanged bottom end of a tubular container, a cutting blade hingedly connected to the underside of said bottom end, an oblong slot in the bottom of said end, said blade hingedly positioned centrally with said slot adjacent one end thereof, said slot provided for foldable placement therein of said cutting blade, a laterally extending ear formed on said blade, for limiting the closing movement of said 45 blade, means for retaining said blade in said slot and the perimeter of the flange on said bottom end adapted for limiting the opening movement of said blade.

In testimony whereof I affix my signature.

EDWARD M. HARRIS.
